UNITED STATES PATENT OFFICE.

OTTO C. SCHULZ, OF CHICAGO, ILLINOIS, ASSIGNOR TO BAUER & BLACK, OF CHICAGO, ILLINOIS, A CORPORATION OF ILLINOIS.

CONTAINER FOR ADHESIVE-BANDAGE ROLLS.

1,134,560.

Specification of Letters Patent.

Patented Apr. 6, 1915.

Application filed January 27, 1913. Serial No. 744,379.

To all whom it may concern:

Be it known that I, OTTO C. SCHULZ, a citizen of the United States, residing at Chicago, in the county of Cook and State of Illinois, have invented certain new and useful Improvements in Containers for Adhesive-Bandage Rolls, of which the following is a specification.

My present invention relates to containers for rolls of adhesive bandages and it has for its object to provide a container of simple and inexpensive construction to contain a roll of maximum size and adapted to be easily assembled.

Adhesive bandage rolls are marketed in a cylindrical container having a slot in its cylindrical wall through which an end of the bandage is drawn and laid over upon the outer surface of this wall with the adhesive side of the bandage against the adjacent surface of the wall to which it may adhere until grasped by the user. In removing a desired portion of the bandage this end is pulled through the slot and the portion cut off by pulling the free portion of the bandage against the edge of a cutter blade mounted upon the outside of the container. This blade extends over the slot and protects the end of the bandage. The roll is placed in the container before one of the circular end or side-walls is positioned. For convenience in loading the container and to permit the container to be opened should the bandage be accidentally pulled within the container, the adjoining edges of the said circular and cylindrical walls are formed to interlock.

It is one of the principal objects of this invention to so construct the adjoining edges of the cylindrical and end walls of a container of this type that the interlocking connection between them will be located wholly without the cylindrical wall so that a roll of diameter equal substantially to the internal diameter of the cylindrical wall may be easily placed in the container and so that also the width of the bandage forming the roll need be only slightly less than the width of the cylindrical walls.

A further object of the invention is to provide a container having a detachable side-wall formed so that it may be easily secured in place and removed with difficulty, whereby useless removal of the side-wall will be discouraged and the exposure of the

bandage to the dust and dirt of the atmosphere minimized.

An additional object of the invention is to provide a container for an adhesive plaster-roll which, in addition to performing these and other important functions, will be cheap to manufacture and neat and pleasing in appearance.

Other objects and advantages of the invention will become apparent as it is better understood from the following description taken in connection with the accompanying drawings illustrating a preferred embodiment thereof.

On the drawings: Figure 1 is a sectional view taken through the center of a container embodying my invention showing a plaster-spool in position therein. Fig. 2 is a side elevation of the same with one of the end or side walls removed.

Referring to the drawings, 3 designates the cylindrical wall, 4 the two end or side walls of the container, and 5 a bandage roll positioned therein. Along each edge of the cylindrical wall 3 is spun or otherwise formed an outwardly extending head 6 and the edges of the end walls 4 are bent from the planes of the end walls as at 7 and formed into beads 8 adapted to interlock with the beads 6 of the cylindrical wall to clamp each bead 7 between a bead 8 and the main body portion of the wall upon which the bead 8 is formed. The portions of the end walls between the beads 8 and the main portions of the walls space the beads from the walls and these portions are preferably inclined to the planes of the end walls at an acute angle. When the beads are spaced from the end walls in this manner they may be easily forced over the beads upon the cylindrical wall in assembling the parts of the container, as in this operation the beads of the end walls are forced back toward the planes of their respective walls. It is however more difficult to remove one of the end walls for to break its interlocking connection with the cylindrical wall the bead upon the end wall must be pulled farther away from its wall.

It will be apparent that, as the beads upon the cylindrical wall extend outwardly, there is no obstruction to the entrance of a roll having an external diameter equaling substantially the internal diameter of the container, and that, as the beads on the end

walls engage the beads on the cylindrical wall without the container, no obstruction is offered by the formation of these walls which will restrict the width of the bandage forming the roll to less than the width of the cylindrical wall.

It is thought that the invention will be understood from the foregoing description, and it is apparent that although both of the end walls have been shown and described as interlocking with the cylindrical wall, only one of them need be so connected, and that various methods may be employed for forming the beads without departing from the spirit and scope of the invention.

I claim:—

A container for a bandage roll comprising a cylindrical wall, and a pair of flat cir-

cular end walls, the edges of said cylindrical wall being rolled outwardly to form beads extending beyond the periphery of said cylindrical wall, the edges of said circular end walls being rolled inwardly to form beads and bent inwardly to form an inclined portion, whereby the beads on said circular end walls are spaced from the flat portion thereof and adapted to engage beneath the beads on said cylindrical wall to force said last-mentioned beads into close engagement with the flat portion of said circular end walls.

OTTO C. SCHULZ.
